UNITED STATES PATENT OFFICE.

RAYMOND B. DU VAL, OF CHICAGO, ILLINOIS, ASSIGNOR TO COMBINATION MACHINE COMPANY, OF NEW YORK, N. Y., A CORPORATION OF DELAWARE.

CONTAINER.

Application filed January 13, 1925. Serial No. 2,116.

This invention is an improvement in containers of sheet material, and more specifically in containers of the slide box type, intended for holding cigarettes, cigars, and like articles.

Cigarettes, small cigars, and like articles, are usually packed in containers of paper board or the like, the cigarettes held in slide movable into and out of a shell.

10 In such containers the cigarettes or cigars are usually arranged in a double row, and for convenience in removing the same, the slide is so constructed that when the tuck-in flap at one end is released and the slide partially withdrawn, not only the ends of the cigarettes or cigars are exposed, but also a portion of the front face of the front row. When the tuck-in flap of such containers is pulled out, and the slide is partially withdrawn, the cigarettes or cigars are presented with their ends in the same plane, and since they are usually compactly arranged, it is difficult to extract a single article without tearing or otherwise injuring the wrapper.

15 No part of the articles extends beyond the slide, so that even when the articles are arranged in a single row, there is nothing separate and distinct from the mass presented to the grasp.

20 30 The position of the tuck-in flap across the ends of the articles, and its tendency to revert to this covering position further impedes and complicates selection and removal of an article.

25 An object of the present invention is the provision of a container of the type mentioned, wherein, when partially withdrawn from the shell, the slide may be moved out of register with the mass of articles, thereby to leave the outer ends thereof free.

30 45 Another object is the provision of a slide so constructed and arranged, that by simple manipulation of the same when partially withdrawn from the shell, the articles may be presented in stepped arrangement, with each article projecting slightly beyond the succeeding.

45 50 Another object is the provision of a construction of container, embodying means enabling attainment among others of the above specified objects, without radical departure from accepted forms and methods of manufacture.

55 To the accomplishment of the foregoing, and such other objects as may hereinafter ap-

pear, the invention consists in the construction and novel combination of parts fully described hereinafter, illustrated in the accompanying drawings, and pointed out in the claims appended hereto, it being understood that various changes in the form, proportion, size and minor details of construction, within the scope of the claims, may be resorted to without departing from the spirit of the invention.

60 65 In the drawings:—

Fig. 1 is a perspective view of a container constructed in accordance with the invention, with the tuck-in flap opened.

Fig. 2 is a similar view with the slide 70 partially withdrawn, and manipulated to project the articles in stepped arrangement.

Fig. 3 is a vertical section of the shell with the slide in the position of Fig. 2.

Fig. 4 is a plan view of the blank from 75 which the slide is formed.

In the present embodiment of the invention, the improved container is composed of a shell 1 of usual construction, having one end open, and the other closed as indicated 80 at 2, and a slide adapted to be inserted into the shell through the open end.

The slide comprises a body portion 3, and ends 4 and 5, each end having a tuck-in flap, the said flaps indicated at 6 and 7. The 85 slide is formed from a blank of suitable material, which is provided with fold defining lines 8, in the nature of creases, scores or the like, defining the ends and tuck-in flaps of the slide, and indicating the lines of fold 90 to form the slide desired.

When folded to receive the cigarettes 9 or other like articles, the ends 4 are bent at right angles to the body, and the tuck-in flaps 6 and 7 are bent to lie substantially 95 parallel with the body, the articles being arranged between the body and the tuck-in flaps. It will be noticed referring to Fig. 4, that the tuck-in flap 7 is of greater width than the flap 6, and this flap 7 is at the 100 bottom or inner end of the slide.

This greater width of flap provides for an increase in friction between the flap and the shell, and lessens the liability to displacement of the flap and the end of the slide, when the slide is partially withdrawn from the shell. After the articles have been placed in the slide, and the slide has been inserted in the shell, the package is wrapped in paper, or in paper foil, or in any other suitable 110.

manner, the wrapping being indicated at 10.

In a package such as described, access is obtained to the articles, by tearing off the wrapper at the open end of the shell, this usually being the top of the package. The tuck-in flap 6 is then released, as shown in Fig. 1, and the slide is partially withdrawn from the shell. In the usual construction, the ends of the articles are in the same plane, 10 the tuck-in flap is in the way, and the top of the slide 3 being in register with the mass of articles prevents the grasping of a single article, or of a file of articles. Each article must be picked out of the slide by grasping 15 the end thereof, an operation which is very liable to damage the article.

In the present construction however, the slide is so constructed that the end thereof provided with the tuck-in flap 6 may be 20 swung laterally partly out of register with the mass of articles.

To permit this swinging movement, the body 3 of the slide is notched at one side edge, preferably at the right when looking 25 at the front of the package, as clearly shown at Figs. 3 and 4. This notch is formed by cutting away a part of the material of the slide body. The notch is formed by two cuts 11 and 12 meeting at 30 somewhat less than a right angle, the notch having a depth of a little more than half the width of the body. The depth of the notch, depends upon how far it is desired that the outer end of the slide swing, and 35 the walls 11 and 12 of the notch are so cut that when the slide is swung to the desired extent, the wall 12 of the notch will abut the shell throughout the length of the wall.

Since the entire slide partakes in this 40 bodily swinging movement, the end 5 of the slide is tilted, that end remote from the notch being lifted. The articles cannot swing laterally with the slide, since they are restrained by the shell to vertical movement, 45 and the several files of the articles, assume a stepped relation, clearly shown in Fig. 2, and indicated in dotted lines in Fig. 3. To return the slide and articles to original 50 position, it is only necessary to swing the slide, and push it in the shell. The return swing of the slide brings the end 5 to normal position, and when the tuck-in flap is replaced, the articles are pushed back into normal position.

55 It will be noted that the provision of the means in connection with the slide whereby it may be manipulated to constrain the articles to assume a stepped relation does not require any departure from shape or 60 method of packing, so that the appearance of the package is not altered, nor is there any change perceptible, until the slide is partially withdrawn. The notch 11-12 may be cut during the formation of the 65 blank from which the slide is made.

It will be obvious that the slide is not necessarily of the character shown and described. The feature which permits the swinging movement is the cutout or notch at the side edge of the slide. This cutout or 70 notch is necessarily the full thickness of the slide, and the principle is applicable to slides having front walls. In this case however, the edge wall of the slide remote from the cutout or notch must be omitted, otherwise 75 the mass of articles would prevent swinging movement.

It is also obvious that the tilting or canting movement of the inner end of the slide may be brought about without partial withdrawal of the slide, in order to protrude cigarettes for convenience in grasping. When the slide end which supports the mass of cigarettes is canted, the cigarettes will be stepped. Any arrangement of slide or 85 other supporting mechanism for the cigarette mass which would permit canting would serve the purpose.

I claim:—

1. A container for cigarettes and the like, comprising a shell, and a slide including means engaging the cigarettes at one end and so constructed it may swing laterally of the shell in the plane thereof to tilt the cigarette end engaging means thereby to 90 shift sundry of the cigarettes longitudinally.

2. A container for cigarettes and the like, comprising a shell, and a slide including means engaging the cigarettes at one end and so constructed it may swing laterally 100 of the shell in the plane thereof to tilt the cigarette end engaging means thereby to shift sundry of the cigarettes longitudinally, when partially withdrawn from the shell.

3. A container for cigarettes and the like, including a shell and a slide, the slide composed of a back and ends, the ends having tuck-in flaps, and means in connection with the slide back to permit lateral swinging 110 movement of the outer end of the slide when it is partially withdrawn from the shell.

4. A container of the class described, including a shell and a slide, the slide including a back and ends, the back notched at 115 one side edge to permit lateral swinging movement of the outer end of the slide when partially withdrawn from the shell.

5. A container of the class described, including a shell and a slide, the slide including a back and ends, the back notched at one side edge to permit lateral swinging movement of the outer end of the slide when partially withdrawn from the shell, one wall 120 of the notch inclined to abut the side wall of the shell throughout its length at the limit of the swinging movement of the slide.

6. A container of the class described, including a shell and a slide, the slide including a back and ends, the back notched at 125 130

- one side edge to permit lateral swinging movement of the outer end of the slide when partially withdrawn from the shell, the inner end of the slide having a relatively long tuck-in flap for the purpose specified.
7. A container comprising a shell and a slide, the slide having a portion thereof at one side edge cut away to permit lateral swinging movement of the outer end thereof when the slide is partially withdrawn.
8. A container comprising a shell and a slide, the slide having a portion thereof at one side edge cut away to permit lateral swinging movement of the outer end thereof when the slide is partially withdrawn, the inner wall of the cut away portion inclined to abut the side wall of the shell throughout its length at the limit of the swinging movement of the slide.
9. A container comprising a shell and a slide, the slide having a portion thereof at one side edge cut away to permit lateral swinging movement of the outer end thereof when the slide is partially withdrawn, said slide open at the edge remote from the cut away portion.

Signed at Chicago in the county of Cook and State of Illinois this 2nd day of January A. D. 1925.

RAYMOND B. DU VAL.
